UNITED STATES PATENT OFFICE

JOHN HENRY WITHERINGTON, OF LOS ANGELES, CALIFORNIA

DESIGN FOR AN IGLOO

Application filed June 13, 1928. Serial No. 27,110. Term of patent 3½ years.

To all whom it may concern:

Be it known that I, JOHN H. WITHERINGTON, a citizen of the United States, residing at Los Angeles, in the county of Los Angeles and State of California, have invented a new, original, and ornamental Design for the Igloo, of which the following is a specification, reference being had to the accompanying drawing, forming part thereof.

Fig. 2 is a plan view showing the exterior outline of the igloo.

I claim:

The ornamental design for an igloo substantially as shown.

JOHN HENRY WITHERINGTON.
